D. W. BOWE,
COMBINATION RAIL SHOE,
APPLICATION FILED OCT. 1, 1919.
1,329,363.

Patented Feb. 3, 1920.

2 SHEETS—SHEET 2.

UNITED STATES PATENT OFFICE.

DAVID W. BOWE, OF DETROIT, MICHIGAN.

COMBINATION RAIL-SHOE.

1,329,363.

Specification of Letters Patent.

Patented Feb. 3, 1920.

Application filed October 1, 1919. Serial No. 327,787.

To all whom it may concern:

Be it known that I, DAVID W. BOWE, a citizen of the United States, residing at Detroit, in the county of Wayne and State of Michigan, have invented a new and useful 5 Combination Rail-Shoe, of which the following is a specification.

This invention aims to provide novel means for holding a railway rail in place 10 and to provide novel means whereby the rail may be held temporarily in an elevated position, before the rail is finally secured in place.

Within the scope of what is claimed, 15 a mechanic may make changes, without departing from the spirit of the invention.

In the drawings:—Figure 1 shows in top plan, a device constructed in accordance with the invention; Fig. 2 is a side elevation 20 showing one rail chair; Fig. 3 is a cross section on the line 3—3 of Fig. 2; Fig. 4 is a cross section showing the rail chair of Fig. 2 as it will appear after one member of the chair has been inverted; Fig. 5 is a perspective 25 of the clamp; Fig. 6 is a perspective showing another rail chair used in combination with the chair of Fig. 2; Fig. 7 is a plan showing a third chair used with the chairs of Figs. 2 and 6.

30 The numeral 1 denotes a stringer which may be made of concrete. Anchor rods 2, 201 and 200 upstand from the stringer 2. The numeral 3 marks a rail having a base flange 4. The rail 3 is supported indirectly 35 on the stringer 1.

Note Fig. 6. The invention includes a chair 5 having recesses 6, in the form of notches, in its transverse edges, the chair having upstanding ribs 7 at its ends. The 40 ribs 7 are provided with upstanding transverse projections 8 in which are located openings 9 adapted to receive the anchor rods 200. Posts 10 upstand from the ribs 7 and have downwardly and inwardly inclined inner edges 11. The chair 5 is located at some distance from the end of the rail 3.

Between the chair 5 and the end of the rail 3 is located a second chair 12 (see Fig. 7). 50 The chair 12 has notches or recesses 14, ribs 15, projections 16 and openings 17 as hereinbefore described in connection with the chair shown in Fig. 6. The openings 17 receive the anchor rods 201.

55 Under the rail is placed a third chair 18 which is a composite structure, the same in-

cluding a main member 19 having a recess 20, ribs 21 and projections 22 as above described. The ribs 21 carry ears 23. The chair 18 has depending flanges 24 engaging 60 the sides of the stringer 1. Note Fig. 3. The main member 19 of the chair 18 is supplied with openings 69, like the openings 9 and 17, but receiving the anchor rods 2. The chair 18 comprises an auxiliary member 25 having flanges 50 coöoperating with the stringer 1, like the flanges 24. In the underside of the member 25, at the free edge thereof there is a notch or seat 51. The free edge of the member 25 has a recess 82, 70 corresponding to the recesses 6 and 14 of Figs. 6 and 7. The auxiliary member 25 is provided with ribs 26 corresponding to the ribs 21 of the main member 19. Posts 27 upstand from the auxiliary member 25 and 75 have downwardly and inwardly inclined inner edges 28 constructed like the parts 11 of Fig. 6. Ears 29 connect the posts 27 with the ribs 26 of the member 25. Pivot elements 30 connect the ears of the member 25 80 with the ears 23 of the main member 19. The construction is such that the members 19 and 25 may be disposed in alinement, or, upon occasion, the auxiliary member 25 may be inverted as shown in dotted line in Fig. 85 2, under which circumstances, the posts 27 engage the main member 19 to hold the auxiliary member in an elevated position.

The invention includes clamps 31 having intermediate recesses 32 (see Fig. 5), the recesses defining end members 33 and 34, the member 34 having a notch or seat 35. Between its ends, the clamp 31 is provided with an opening 36. The under surface of the end member 33 is inclined as shown at 37. 95

In practical operation, the auxiliary members 25 of the chairs 18 are inverted as shown in dotted line in Fig. 2, so that the posts 27 rest on the main member 19. The flange 3 of the rail 4 is inserted into the seats 51 of 100 the auxiliary members 25. The rail, therefore, cannot slide transversely, and is held temporarily in an elevated position, facilitating track work of any kind. The auxiliary member 25 may be swung backwardly 105 until it is alined with the main member 19. Then, the inclined edges 28 of the posts 27 and the inclined edges 11 of the posts 10 guide the rail, as it moves downwardly, so that the base flange 4 of the rail is received 110 between the ribs 7—7, 15—15, 21—21 and 26—26. Prior to the lowering of the rail, as

above described, shims 42 are mounted on the stringer 1, the ends of the shims being received in the recesses 6, 14, 20 and 22. Thus, a continuous surface is presented, 5 whereon the base flange 4 of the rail 3 rests. The notches 35 of the clamps 31 receive the projections 22 on the ribs 21 of the main member 19 of the chair 18, the inclined surfaces 37 of the clamps engaging the base 10 flange 4 of the rail 3 (Fig. 3). Nuts 38 are threaded on the anchor rods 2 and hold the member 19 in place, the nuts being received in the recesses 32 of the clamps. The rods 2 project through the openings 36 of the 15 clamps 31, nuts 39 being threaded on the upper ends of the rods to hold the clamps in operative position. A like clamp construction is used in connection with the chairs 5 and 12, the clamps of the chair 12 being denoted by the numeral 40 in Fig. 1 and co-operating with nuts 41 on the anchor rods 201. The anchor rods 200 together with their nuts 41 hold the clamps in operative 20 relation to the chair 5, as Fig. 1 will make 25 manifest.

Having thus described the invention, what is claimed is:—

1. In a device of the class described, a stringer; spaced chairs on the stringer and 30 having upstanding ribs, the chairs having notches in their transverse edges; shims on the stringer and having their ends received in the notches; and a rail supported on the shims and the chairs and received between 35 the ribs of the chairs.
2. In a device of the class described, a stringer; a rail chair thereon and having ribs each provided with a transverse projection; a rail including a base flange received 40 between the ribs; a clamp engaging the base flange of the rail and having a notch receiving the projection; and a securing device connecting the stringer and the clamp.
3. In a device of the class described, a 45 stringer; a rail chair thereon and having ribs; a rail including a base flange received

between the ribs; means for securing the rail to the chair and the stringer; and posts constituting a part of the chair, the posts having inclined edges serving to guide the rail 50 between the ribs.

4. In a device of the class described, a rail chair having ribs each provided with a transverse projection; a rail including a base flange received between the ribs; a clamp 55 engaging the base flange of the rail and having a notch receiving the projection; means for securing the clamp to the chair; and posts constituting a part of the chair, the posts having inclined edges serving to guide 60 the rail between the ribs.

5. A rail chair comprising hingedly connected main and auxiliary members forming a rail support when said members are alined, the auxiliary member having upstanding 65 rail-guiding posts, the auxiliary member being invertible to cause the posts to engage the main member, thereby to maintain the auxiliary member elevated with respect to the main member and to render the auxiliary 70 member effective as a temporary rail supporting means.

6. A rail chair comprising hingedly connected main and auxiliary members having upstanding ribs and provided with posts 75 having inclined inner edges serving to guide a rail between the ribs, when said members are alined, the auxiliary member being invertible to cause the posts to engage the main member, thereby to maintain the auxiliary member elevated with respect to the main member and to render the auxiliary 80 member effective as a temporary rail supporting means.

In testimony that I claim the foregoing as 85 my own, I have hereto affixed my signature in the presence of two witnesses.

DAVID W. BOWE.
